BY
Merrill M. Blackburn
ATTORNEY

UNITED STATES PATENT OFFICE

JOHN R. GRAHAM, OF LINWOOD, IOWA

MAIL BOX

Application filed December 26, 1930. Serial No. 504,701.

The present invention relates to improvements in mail boxes and concerns more especially such as are adapted for use on rural routes. Among the objects of this invention are to provide a mail box which is so constructed that it may be set back away from the pavement of country roads so as to give plenty of clearance between the pavement and the mail box and yet the box is so constructed that for the rural mail carrier to deliver mail thereto it will not be necessary for him to drive off from the pavement; to provide a mail box having sufficient height to take in most parcel post packages which are sent through the mail; to provide a mail box which is simple in construction and easy in operation; to provide a mail box which may be left unlocked for the insertion of mail and which will automatically be set in locking position when opened; to provide in a mail box of the type described means for supporting packages away from the bottom of the box so that in case snow or rain should get into the box, the packages will be kept out of contact therewith; and such further objects, advantages and capabilities as will hereafter appear and as are inherent in the construction disclosed herein. My invention further resides in the combination, construction and arrangement of parts illustrated in the accompanying drawing and, while I have shown therein what is now considered the preferred embodiment of this invention, I desire the same to be understood as illustrative only and not to be interpreted in a limiting sense.

In the drawing annexed hereto and forming a part hereof,

Fig. 1 is a plan view of the structure shown in Fig. 2, in which the door is shown in open position;

Fig. 2 is a vertical section substantially along the plane indicated by line 2-2, Fig. 1;

Fig. 3 is a perspective view of my new mail box with the door closed and the signal flag raised;

Fig. 4 is a fragmentary transverse section through the door taken substantially along the plane indicated by the line 4-4, Fig. 2;

Fig. 5 is a fragmentary section, substantially along the plane indicated by the line

2-2, Fig. 1, on a somewhat larger scale than that illustrated in said figure;

Fig. 6 is a fragmentary section through one flange of the door, in a plane at a right angle to that illustrated by the line 4-4, Fig. 2 and taken just inside of the edge of the flange;

Fig. 7 illustrates a hook whereby the postman may reach the handle of the door to cause opening thereof.

Reference will now be made in greater detail to the annexed drawing in which like reference characters denote like parts in the several views. In this drawing the mail box is denoted in general by the numeral 1 and its legs by the numeral 2. The door 3 is connected by any suitable hinges 4 to the door sill 5. It is considered desirable to provide a slot 6 covered by a hinged plate 7 so that, in event the door is locked when the postman arrives, he may drop letters and small parcels into the box rather than having to carry them away. Handle 8 is provided whereby the door may be pulled outwardly to open the same, and a handle 9 having a hook 10 upon one end is used by the postman to engage the handle 8 on the door so as to pull the door open without the necessity of driving off the pavement. A lock 11 of the self-locking night latch type is secured to the inside of the door and its latch cooperates with the cross piece 12 extending across the upper part of the front of the box and overhanging by the edge 13 of the box top which serves as a sort of porch for the door to keep as much as possible of the rain away from the top edge of the door and thus reduce the amount of water getting into the box between the door and the cross piece 12. Extending upwardly from the overhang 13 are a pair of lugs 14 between which is pivoted the staff 15 of the flag 16 whose purpose will be readily understood. Integral with the staff is a hook 17 which is so bent as to engage the edge of the overhang 13 and prevent the flag from being blown or jarred down into the solid line position shown in Fig. 2. This hook 17 is of resilient material and either integral with the staff 15 or secured thereto.

The door 3 is provided at its lateral edges with wide flanges 18 extending throughout

the length thereof, as best illustrated in Figs. 2 and 4. A casing 19, illustrated in end view in Fig. 4, is secured along its edges to the door 3 and flange 18. This casing forms a slideway for the slides 20 which carry the letter box 21 (Figs. 1 and 2). The inner ends of the slide bars 20 are bent substantially at a right angle to the length thereof and are of such a length that they will just slide freely within the channel formed by the door 3, flange 18 and channel member 19. Adjacent its upper end, the door 3 is provided with a pair of casings 23 within which are mounted rollers 24. These rollers project through openings in the door 3 and furnish anti-friction means upon which the slide bars 20 may move and by means of which binding between these slide bars and the door 3 is reduced to a minimum. These rollers extend just far enough through the door to prevent contact of the bars 20 with the inner face of the door.

A strap 25 is fastened to the inside of each flange 18, the same being bent into the form illustrated in Fig. 6 for the support of a pulley 26 mounted upon a pivot 27. The chain 28 passes around the pulley 26 and inside of the strap 25 and is secured at one end to the part 22 of the bar 20, while its other end is adjustably secured to a fastening member 29 on the inside of the box. This provides an adjustment which will be referred to hereinafter. While I have shown the end of strap 25 bent inwardly to form a stop 30 against which the arm 22 may strike to limit the outward motion of the box 21, this stop might be provided in the form of a pin secured to the flange 18. However, the structure illustrated is considered stronger than if a pin were substituted for the projection 30 and it is for this reason, primarily, that the present structure is preferred. However, ease of assembly and cheapness of construction are also considered when deciding upon this construction. It is of course understood that the strap 25 may be secured in place either by means of rivets or by spot welding or by other suitable means, though the use of spot welding is preferred. The ends of the bars 20 are bent inwardly and downwardly, as illustrated at 31, to support the letter box 21 away from the flanges 18 far enough to permit the box to come to rest between the upper ends of members 19 when the door is closed.

If thought desirable the strap 25 might be formed as a complete loop and have the pulley 26 mounted therein. This strap may be spotwelded to the flange 18, thus doing away entirely with passing any rivets through this flange. Such construction would be simpler than that illustrated in the present drawing, inasmuch as the assembly of the pulley in the loop would be a simple matter and the assembly of this unit upon the flange 18 would likewise be a simple matter. However, I pre-

fer a structure more nearly like that shown in Fig. 6.

The lock 11 has a latching plunger 32 which engages inside of the cross piece 12 at the top of the box. This lock is so constructed that when the latching dog is drawn back into the lock by means of the key inserted into the key hole 33 it may be fastened back by appropriate manipulation of the handle 34 projecting from the lock 11. When this lever 34 is pulled upwardly, the latching dog 32 is released and extended outwardly into the position indicated in Figs. 1 and 2. The means for automatically releasing this latching dog so that the lock will fasten the door after it has been closed is the spring pressed dog 35 which is pivoted on the projection 36 extending from the box 21. This dog 35 is so arranged that when the door is closed the dog will slide over the handle 34 without having any effect upon the lock. On the other hand, when the door is opened and the box moves upwardly and outwardly the dog 35 strikes the handle 34 and moves the same upwardly to release the latching dog 32. Therefore, when the door is again closed, this latching dog engages behind the cross piece 12 and holds the door in closed position.

Supporting means 37, illustrated as a piece of heavy wire netting, is arranged in the bottom of the mail box to support mail matter away from the box bottom. Therefore, if any rain or snow should get into the box and collect on the bottom thereof, this supporting means would hold the mail up and prevent it from becoming wet. Ridged reinforcing strips 38 are preferably secured along the lateral edges of the door 3 in order to render the same more rigid and less likely to be bent during use. If deemed desirable, the posts 2 may be extended upwardly so as to reinforce the corners of the box. Since these posts are of angle iron construction, it would be necessary to make some further changes in this construction if the posts at the front corners of the box were to be extended above the bottom of the door 3. Inasmuch as this is not believed to be an essential change, these changes have not been illustrated.

In the following description of the operation of this construction, it will be assumed that the mail box has been set up along the roadside at a distance from the travelled way which corresponds to approximately four feet from the edge of pavement. This distance has been selected in order that the box will be clearly outside of the line of travel unless a vehicle should turn farther to the right of its course of travel than is expected. The box is not, however, so far from the roadway that the letter box 21 will not be within easy reach of a vehicle standing upon the pavement. Therefore, when the postman drives up to the box and takes hold of the handle 8 with his door

opening tool 9 he can swing the door outwardly and bring the box 21 closely adjacent the side of his car. When the door is in closed position, as illustrated in Fig. 3, the lower ends 22 of the slide bars 20 are at the lower ends of the flanges 18 and channel members 19, the box 21 being approximately opposite the upper ends of the channels 19. As the door 3 closes, the bars 20 carrying the box 21 slide downwardly to their lowermost position and the weight of the bars 20 and box 21 suspended on the lower end of chain 28, tends to hold the door 3 closed, even when the latch 32 is not released so as to engage the cross piece 12. As the door is opened, the chains 28 are pulled over the pulleys 26 and this results in extending the bars 20, thus carrying the box 21 out to a position easy of access to the postman sitting in his vehicle. As the door is opened, the dog 35 engages the projecting arm 34 and pulls it upwardly, releasing the latch 32 so that this is allowed to project into latching position. When the door is again closed the latch 32 snaps in behind the cross bar 12 and locks the door closed. As the door is being closed, the weight of the box 21 and the bars 20 causes these to move downwardly so as to permit the door to close, the letter box being entirely within the mail box. I prefer to mount these boxes on suitable slabs of cement or concrete which will be heavy enough to prevent the boxes from being easily turned over but light enough moderately easily moved, if found desirable that they be moved.

It will of course be understood that this specific description of structure set forth above may be departed from without departing from the spirit of my invention as set forth in the appended claims.

Having now described my invention, I claim:

1. A mail box having a door hinged to one side thereof, said door having guideways for slides, slides in said guideways, a mail container carried by said slides, and means to cause projection of said slides and container when the door is opened.

2. A mail box as defined by claim 1 in which the door has lateral flanges to form guides for packages placed thereon so that said packages will slide on the door and be delivered into the box.

3. A mail box as set forth in claim 1 having a lock for locking the door closed, means for holding the lock in non-locking position, and means for releasing the lock when the door is opened so that when the door is closed it will lock.

4. A mail box as set forth in claim 1 having friction reducing means in connection with the door to reduce the friction of the slides as the door is opened and closed.

5. A mail box having a substantially full length door hinged to one side thereof, said

door having lateral flanges, casing members mounted on said flanges and forming therewith slideways for slide-bars, slide-bars mounted in said slideways and movable longitudinally therein, a mail container carried by said slide-bars, and means connected to said slide-bars to cause sliding thereof in said slideways and projection of the container beyond the door when the latter is opened.

6. A structure as defined by claim 5 having pulleys mounted on the door flanges and in which the means connected to the slide-bars comprises flexible means passing over the pulleys to a point of attachment inside the mail box.

7. A mail box comprising, in combination, a package receiving container having an open side, a door hinged thereto to close said side, guideways on the inner face of said door, slides movable in said guideways and carrying a mail receiving box, flexible means sustaining the weight of said slides and box, the slides and box serving to hold the door closed when closed and not locked.

In witness whereof, I hereunto subscribe my name to this specification.

J. R. GRAHAM.
